Primary Examiner — Samantha Wood(74) *Attorney, Agent, or Firm* — Jose Cherson Weissbrot(57) **CLAIM**

The ornamental design for a tricep rope, as shown and described.

DESCRIPTION

FIG. 1 is a front perspective view of a tricep rope, showing my new design;

FIG. 2 is a rear perspective view thereof;

FIG. 3 is a front elevation view thereof;

FIG. 4 is a rear elevation view thereof;

FIG. 5 is a left side elevation view, the right side elevation view being a mirror image of FIG. 5;

FIG. 6 is a top plan view thereof;

FIG. 7 is a bottom plan view thereof;

FIG. 8 is a partial enlarged view of FIG. 1;

FIG. 9 is a partial enlarged view of FIG. 2; and,

FIG. 10 is a partial enlarged view of FIG. 5.

The dash-dash broken lines in the drawings depict portions of the tricep rope that form no part of the claimed design. The dash-dot-dash lines in the figures are for an-notating enlarged views, which form no part of the claim design.

1 Claim, 6 Drawing Sheets(56)
